UNITED STATES PATENT OFFICE

ROBERT H. NICHOLSON, OF MEADVILLE, PENNSYLVANIA, ASSIGNOR TO HOOKLESS
FASTENER COMPANY, OF MEADVILLE, PENNSYLVANIA, A CORPORATION OF PENN-
SYLVANIA

DESIGN FOR A PULL FOR A SLIDE FASTENER

Application filed January 29, 1929. Serial No. 29,829. Term of patent 14 years.

To all whom it may concern:

Be it known that I, ROBERT H. NICHOLSON, a subject of the King of England, residing at Meadville, in the county of Crawford and State of Pennsylvania, have invented a new, original, and ornamental Design for a Pull for a Slide Fastener, of which the following is a specification, reference being had to the accompanying drawing, forming a part thereof.

In the drawing:

Figure 1 is a plan view of a pull for a slide fastener showing my new design; and

Figure 2 is a side elevation of the same.

I claim:

The ornamental design for a pull for a slide fastener substantially as shown.

In testimony whereof I affix my signature.

ROBERT H. NICHOLSON.

CERTIFICATE OF CORRECTION.

Design Patent No. 79,905.

Granted November 12, 1929, to

ROBERT H. NICHOLSON.

It is hereby certified that error appears in the printed specification of the above numbered patent requiring correction as follows: Page 1, second column, line 2, strike out the words "plan view" and insert instead "front elevation"; and that the said Letters Patent should be read with this correction therein that the same may conform to the record of the case in the Patent Office.

Signed and sealed this 7th day of January, A. D. 1930.
